UNITED STATES PATENT OFFICE

146,928

DESIGN FOR A PERFUME CONTAINER OR THE LIKE

Edward P. Schreyer, Ridgefield, Conn.

Application August 23, 1946, Serial No. 132,770

Term of patent 14 years

(Cl. D86—10)

To all whom it may concern:

Be it known that I, Edward P. Schreyer, a citizen of the United States and residing at Ridgefield, in the county of Fairfield and State of Connecticut, have invented a new, original, and ornamental Design for a Perfume Container or the like, of which the following is a specification; reference being had to the accompanying drawing, forming part thereof, and in which

Fig. 1 is a side elevation of the perfume container or the like, showing my new design,

Fig. 2 is a top elevation thereof, and

Fig. 3 is a bottom elevation thereof.

I claim:

The ornamental design for a perfume container or the like, substantially as shown.

EDWARD P. SCHREYER.
